HAIR CLIP

Lewis E. Thatcher, Chicago, Ill., assignor to Gaylord Products, Incorporated, Chicago, Ill., a corporation of Delaware

Filed Nov. 9, 1964, Ser. No. 82,521

Term of patent 14 years

(Cl. D86—10)

FIG. 1 is a top plan view of a hair clip showing my new design;

FIG. 2 is an elevational view of one side thereof, the other side view being the same;

FIG. 3 is a bottom plan view thereof;

FIG. 4 is an elevational view of the front thereof; and

FIG. 5 is an elevational view of the rear thereof.

I claim:

The ornamental design for a hair clip, substantially as shown.
